CLAIM

The ornamental design for a package, as shown and described.

DESCRIPTION

FIG. 1 is a front view of package showing our new design; FIG. 2 is a rear view thereof; FIG. 3 is a left side view thereof; FIG. 4 is a right side view thereof; FIG. 5 is a top view thereof; FIG. 6 is a bottom view thereof; FIG. 7 is a perspective view thereof, showing the package prior to assembly; FIG. 8 is a perspective view thereof, showing the package in a partially assembled configuration; and, FIG. 9 is a perspective view thereof, showing the package in a fully assembled configuration.

The broken lines in the drawings depict environmental subject matter and form no part of the claimed design.
